COMBINATION PORTABLE TUBING BOARD
AND TUBING RACKDon W. Lee, Oklahoma City, Okla., assignor to
Skelly Oil Company, Tulsa, Okla.

Application July 16, 1936, Serial No. 91,015

5 Claims. (Cl. 211—60)

My invention relates to new and useful improvements in the combination of a portable tubing board and tubing rack with oil well derricks, and has for its object to provide a tubing board and rack which may be quickly and easily attached to the derrick at any desired level. Another object of my invention resides in providing a relatively light tubing board which can be easily handled yet which is sufficiently sturdy 10 to withstand any shocks to which it may be subjected.

In operating oil wells, it becomes necessary from time to time to pull the tubing out of the well for repairs and cleaning out the well itself. 15 In this event, under the usual practice, the string of tubing is raised by the conventional elevator attached to a steel cable on a block and pulley high in the derrick, and a reel on the floor operated by an engine. The string of tubing is suspended by means of a tubing spider and the tubing is unscrewed in two, three or four joint 20 lengths or stands as the case may be. Each stand is then raised slightly, its lower end pushed to one side and is then lowered to the derrick 25 floor. As each stand is unscrewed, swung to one side and lowered to its place on the floor, a workman standing on a tubing board located at a suitable level in the derrick, depending upon the 30 length of the stands, leans the upper end of each stand against the tubing board and then detaches the elevator therefrom. The elevator is then lowered to the floor and is attached to the top of the next section of the string in the well, and the operation heretofore described is repeated 35 until the string has been entirely pulled out. In re-running the tubing, obviously the reverse of the operation above described is followed.

The tubing boards heretofore employed have been heavy and bulky due to the fact that the 40 stands had to be leaned against the same, which obviously created a dangerous hazard for the workman standing thereon. These tubing boards were made of heavy oak timber reinforced with steel and weighed approximately from 300 to 45 400 pounds. They were laid across the derrick at any suitable level and adapted to span the distance between the girths at that level. Due to the construction of the conventional derricks, 50 i. e., wider at the bottom and gradually decreasing in width towards the top, the tubing boards had to be sufficiently long to span the width of the derrick in the lower part thereof (about 14 feet) for handling tubing in single joints. The 55 bulk and weight of these boards made it difficult

to move them from place to place in the derrick, and from well to well, as needed.

It is to overcome these disadvantages and difficulties that I have designed a portable tubing board of comparatively light weight for the workman to stand upon, and a co-operating portable rack against which the upper ends of the stands of tubing are adapted to rest. The tubing board is attached to one of the girths on one side of the derrick at the desired height, and the rack is 10 attached to the same girth at one side of the tubing board in a corner of the derrick.

Furthermore, by my invention I provide a safer place for the tubing board workman in performing his duties in that the individual stands of 15 tubing are only temporarily leaned against the tubing board to enable the workman to disengage the elevator from the stand, after which the stand is pushed to one side and leaned against the rack where it remains until re-run in the 20 well.

A still further object of my invention is to provide a tubing board in combination with a rack, the latter being reversible and adapted to be attached to any corner of the derrick with equal 25 facility, thus making it possible to rest the stand of tubing on any side of the derrick.

With the above and other objects in view which will appear as the description proceeds, my invention consists in the novel features herein set 30 forth, illustrated in the accompanying drawings and more particularly pointed out in the appended claims.

Referring to the drawings in which numerals of like character designate similar parts throughout the several views,

Fig. 1 is a front elevation of a derrick with my improved tubing board and rack in place on the side thereof. For the purposes of illustration I have shown two such boards and racks in place 40 at different levels in the derrick.

Fig. 2 is an enlarged detail perspective view of the tubing board.

Fig. 3 is an enlarged detail perspective view 45 of the tubing rack, and

Fig. 4 is an enlarged perspective view partially broken away showing my combined tubing board and rack in place in the derrick.

In the drawings, 1 designates a conventional 50 derrick located over an oil well and extending upwardly for approximately 75 or 100 feet. The upper portion of the derrick is provided with a small platform 2 adapted to carry the conventional block and pulleys (not shown) used in 55

raising the tubing from the well or re-running said tubing into said well.

In Fig. 2 I have shown a perspective view of my improved tubing board or platform 3 which may be composed of any suitable material such as wood or metal, preferably rough oak planks of a thickness of approximately 1 inch and about 7 feet in length. Several of these planks are secured together edgewise to form a tubing board approximately 2½ feet in width, and if desired, 10 I may protect the edges of the board by bounding the assembled platform with metal strips or the like 4 secured thereto in any suitable manner.

The tubing board 3 rests upon supporting rods 15 5 underlying either end thereof and secured in place preferably by a series of U-bolts which project upwardly through the board and are fastened by means of nuts 6. Each of these rods 5 is provided at one end with a yoke 7 adjustably 20 secured to the rods, preferably by a telescopic connection and set screw 8. In the form shown in the drawings these rods 5 are tubular in shape so as to receive the supporting shanks of the yokes 7 which may be moved inwardly or outwardly to 25 the desired position and retained in place by the set screws 8 which extend through the tubular rods and bear against the supporting shanks of the yokes.

The tubing board is secured in place at the 30 desired height in the derrick in the manner shown in Fig. 4. The yokes 7 embrace an adjacent girth 9 and are clamped thereon by suitable bolts 10, the inner side of the board or platform being supported by chains 11 which extend from the girth 35 12 next above and are secured at the lower ends to the tubing board by rings or the like 13.

At a suitable point on the inner side of the tubing board I provide a finger board 14 preferably comprising an angle iron secured by bolts 40 or screws 15, and which projects inwardly from the tubing board toward the center of the derrick for the purpose hereinafter set forth.

Referring to Fig. 3 I have shown my improved tubing rack for use in conjunction with and as a 45 part of the tubing board assembly. This rack consists of two supporting legs 16 secured at their upper extremities to a cross bar or rail 17 and carrying at their lower ends yokes 18 similar to the yokes 7 heretofore mentioned. These yokes 50 18 are adapted to embrace the girth 9 at a point immediately adjacent the tubing board 3 toward the corner of the derrick as shown in Fig. 4 and are disposed at an upward angle to the vertical. The outer end of the cross bar 55 17 extends slightly beyond the adjacent supporting leg 16 and is threaded to receive an elbow 19 which in turn receives the threaded end of a brace member 20, the other end of which carries a yoke 21. This yoke 21 embraces one of the 60 vertical legs 22 of the derrick to rigidly retain the rack in the proper position with respect to the tubing board. The opposite end of the cross bar 17 is provided with a finger 23 which preferably projects at right angles to the cross bar 65 for a distance of approximately 14 inches for the purpose hereinafter set forth.

When my improved tubing board and rack are in position on the derrick, the top of the cross bar 17 is substantially 3 feet above the level of the tubing board, the rack being located in one corner of the derrick and the board being positioned immediately adjacent to the rack.

In operation a workman is stationed on the tubing board 3 and due to the height and location 70 75 of the finger 23 and the cross bar 17, the

rack structure serves as a supporting rail for the workman while performing his duties of removing or re-running tubing from or into the well.

As the individual stands of tubing are removed and unscrewed from the string in the conventional manner, the workman on the tubing board temporarily rests the tubing against the finger board 14 with its lower end on the floor of the derrick while he detaches the elevator used in hoisting the tubing. After detaching the elevator, 10 the tubing is swung around with its lower end still resting on the floor of the derrick until its upper end rests on the cross bar 17 of the tubing rack where it remains until re-run in the well. This operation is repeated until the entire string has 15 been removed from the well, the pipe finger 23 on the rack serving to keep the pipe or tubing from slipping off the rack. As before pointed out, this finger projects approximately 14 inches from the front side of the rack so that several tiers or 20 lines of tubing may be leaned against the rack without danger of the tubing slipping toward the inside of the derrick.

It will be noted that this pipe finger 23 is 25 always on the side of the rack away from the corner of the derrick and in order to enable a single rack to be used in any corner of the derrick, the supporting brace 20 is rotatable on the projecting end of the cross bar 17 so that it 30 may be swung from one side to the other when the position of the rack is shifted. The threaded connection of the elbow 19 to the end of the cross bar 17 permits this adjustment.

The chief advantages of my improved combination of tubing board and rack are their 35 lightness and the ease with which they may be handled in moving from place to place, and the fact that they provide a safer place in which the tubing-rack workman performs his duties. The tubing boards now in common use require 40 a large truck for their transportation from one well to another and at least four men to load and unload them. On the other hand, the tubing board of my invention weighs about one 45 half as much as the old conventional tubing boards and can be loaded or unloaded by two men, and the rack weighs less than 50 pounds. Either of these parts of my invention may be 50 hauled on the tool rack of an ordinary oil field automobile.

It will thus be seen that with my improved structure, an operator with a number of wells in an oil field would require a far less number of devices for operation than the old type here- 55 fore employed.

From the standpoint of safety, as has been pointed out above, the workman can brace himself in performing his work by grasping either the pipe finger 23 or any convenient portion of the rack and, furthermore, the supporting chains 60 may also serve as a protection from falling, thus reducing the hazards which have heretofore been prevalent when the tubing rested against the board itself.

From the foregoing it is believed that the 65 construction operation and advantages of my invention may be readily understood by those skilled in the art, without further description, it being borne in mind that numerous changes may be made in the details of structure herein disclosed 70 without departing from the spirit of my invention as set forth in the following claims.

What I claim and desire to secure by Letters Patent is:

1. A rod rack for well derricks including a 75

rod supporting cross bar, spaced legs depending from said cross bar, means for securing the free ends of said legs to one of the girths of said derrick, a lateral brace member pivotally mounted on said cross bar, and having at its free end means for securing the same to a leg of said derrick, said pivotal connection permitting the reversal of said brace to facilitate its attachment to any leg of the derrick.

10 2. A rod rack for well derricks including a rod supporting cross bar, spaced supporting legs depending from said cross bar, means for securing the free ends of said legs to one of the girths of said derrick, a lateral brace member secured at 15 one end to said cross bar, having at its other end means for securing the same to a leg of said derrick, and a rod retaining finger extending upwardly from one end of said cross bar.

3. A rod rack as claimed in claim 2 wherein 20 said brace member is pivotally mounted on said

cross bar to permit its reversal for engagement of its free end to any leg of the derrick.

4. A rod rack for well derricks including a rod supporting cross bar, spaced legs depending from said cross bar, means for securing the free ends 5 of said legs to one of the girths of said derrick, a rod retaining projection on one end of said cross bar, a lateral brace member at the other end of said cross bar, and means for securing said brace member to said derrick.

10 5. A rod rack for well derricks including a rod supporting cross bar, spaced legs depending from said cross bar, a yoke mounting at the free end of each of said legs embracing one of the girths 15 of said derrick, a lateral brace member secured 15 at one end to said cross bar, and having at its other end a yoke mounting for securing the same to one of the upright legs of said derrick.

DON W. LEE. 20
